UNITED STATES PATENT OFFICE.

JOHN F. HUBER, OF BUFFALO, NEW YORK, ASSIGNOR TO GEORGE W. POUND, OF BUFFALO, NEW YORK.

MANIFOLD-BOOK OR SALES-SLIP HOLDER.

1,213,877.

Specification of Letters Patent. Patented Jan. 30, 1917.

Application filed July 8, 1914. Serial No. 849,727.

To all whom it may concern:

Be it known that I, JOHN F. HUBER, a citizen of the United States, residing at Buffalo, in the county of Erie and State 5 of New York, have invented new and useful Improvements in Manifold-Books or Sales-Slip Holders, of which the following is a specification.

This invention relates to a manifold book 10 or sales slip holder of that type in which a triplicate record is made of sales, one for the customer, one for the clerk making the sale and another for the use of the accounting department of the establishment.

15 It is the object of this invention to produce a manifold book or sales slip holder of this character which will permit of using detached sheets each containing an original or front section, an intermediate or duplicate 20 section and a rear or triplicate section, and so mounting a plurality of such sheets that the same may be conveniently manipulated in connection with suitable carbon sheets for producing a triplicate record and also 25 easily replaced with new sheets when the supply is exhausted.

In the accompanying drawings: Figure 1 is a perspective view of a manifold book or sales slip holder embodying the preferred 30 form of my invention. Fig. 2 is a cross section of the same taken in line 2—2, Fig. 1. Fig. 3 is a fragmentary longitudinal section taken in line 3—3, Fig. 1. Fig. 4 is a perspective view of the carbon sheets 35 and the supporting sheet of the same which is employed in the construction shown in Fig. 1. Fig. 5 is a perspective view of one of the record sheets. Fig. 6 is a perspective view of a part of the clamping device 40 whereby a package or pile of record sheets is held in place on the backing of the holder. Fig. 7 is a perspective view showing another arrangement of the carbon sheets and supporting sheet which may be employed 45 in this device.

Similar characters of reference indicate corresponding parts throughout the several views.

The body of this manifold book or sales 50 slip holder may be variously constructed,

that shown in the drawings being suitable and comprising a backing 1 and a cover 2, these parts being connected at two of their opposing transverse edges by a flexible hinge 3 so that they may be opened or closed 55 in the manner of a book for the purpose of covering or uncovering the sales slips or sheets and the clamping devices arranged between the same. This flexible connection between the backing and the cover is pref- 60 erably effected between the lower transverse edge of the bottom section and the upper edge of the top section, as shown in Fig. 1, although these parts may be otherwise connected, if desired. The cover and the 65 hinge of the backing may also, if desired, be omitted altogether inasmuch as they form no essential part of this invention. Upon the front or face of the backing is arranged the pile or pack of sales slips or 70 record sheets 4 each of which is folded or doubled upon itself twice so as to approximate the form of the letters S or Z and produce a front or original slip leaf or section 5, an intermediate or duplicate slip 75 leaf or section 6 connected at one of its transverse edges with one of the transverse edges of the front section, and a rear or triplicate slip leaf or section 7 connected at one of its transverse edges with the other 80 transverse edge of the intermediate section while the other transverse edge of this rear section is provided with a tab 8 for attaching the same to the face of the backing. In the construction shown in Figs. 1 and 5 85 85 each of the record sheets is so folded that the lower transverse edge of the front section is free, the intermediate section is connected at its upper and lower edges with the upper and lower ends, respectively, of 90 the front and rear sections and the attaching tab of the rear section is arranged at the upper end of the rear section. A plurality of such folded sheets are arranged in the form of a pile or package one above 95 the other upon the face of the backing and are removably secured thereto or mounted thereon so that each sheet may be detached from the pile and the backing independ- 100 ently of the other sheets. The means for

thus detachably mounting the several record sheets on the backing comprises two binding pins or posts 9, 9 fixedly mounted on the upper part of the backing so as to 5 project forwardly therefrom at right angles thereto and transversely in line. The tab of each record sheet is provided with a pair of binding openings 10, 10 which are adapted to receive the binding pins of the 10 backing and hold the sheets against transverse displacement thereon.

The several record sheets or sales slips are held on the backing by a clamping device which is so constructed as to permit each 15 sheet to be readily removed from the binding pins or posts independently of the other sheets, the preferred means for this purpose comprising a U-shaped spring having a transverse bar 11 adapted to press against 20 the front side of the pile of tabs of the sheets, two longitudinal side bars or arms 12, 12 projecting downwardly from opposite ends of the transverse bar and along the face 25 of the backing on opposite sides of the pile of sheets, two longitudinal guide loops or slotted portions 13 arranged at the lower ends of the longitudinal bars, and two guide pins 14 arranged on the front side of the backing on opposite sides of the pile of 30 sheets and each having a head 15 at its front end. Each of said guide loops receives one of said guide pins and is confined between the backing and the head of the respective guide pin so that these loops are capable of 35 sliding to a limited extent on these guide pins but are prevented from being lifted from the backing.

When applying a pile of record sheets to the backing the clamping spring is drawn 40 upwardly until the lower ends of its guide loops engage with the guide pins, thereby leaving the space above the binding pins free to permit the perforated tabs of the record sheets to be slipped over the binding 45 pins. After the pile of sheets has been thus applied to the binding pins the clamping spring is pushed downwardly and its cross bar is sprung forwardly and engaged with the front side of the pile of tabs above the 50 binding pins, whereby the resilience of the spring arms or side bars of the clamp is caused to press the several tabs against each other and against the backing and hold the same reliably in place.

55 In order to confine the clamp against swaying laterally in a direction parallel with the face of the backing, a retaining device is provided which preferably comprises two retaining pins 16 mounted on the upper part 60 of the face of the backing and projecting forwardly therefrom and engaging with the inner sides of the side bars or arms of the clamp, thereby permitting the clamp to slide freely into and out of its operative position

lengthwise of the backing and pile of sheets 65 but preventing lateral movement thereof, whereby these parts are always retained in the proper position which will permit convenient and quick manipulation of the sheets.

Upon making the record of a sale on the front section of the sales sheet a manifold copy of the same is produced on the intermediate and rear sections by means of two carbon sheets one of which is interposed between the front and intermediate sections 70 and the other between the intermediate and rear sections of the sheet. These carbon sheets may be variously mounted on the backing so as to permit of conveniently assembling the same with the several sections of the record sheet and separating the same therefrom. In the construction shown in Figs. 1, 2, 3 and 4 the means for mounting these carbon sheets on the backing comprises 75 a supporting sheet 17 adapted to be placed between the lowermost record sheet and the face of the backing and provided at its upper end with two openings or perforations 18 which receive the binding pins and a flexible hinge 20 connected with the upper edge 80 of the supporting sheet and adapted to be folded forwardly and downwardly over the tab of the foremost record sheet and provided with two openings or perforations 21 85 which receive the binding pins. Beyond its binding openings 21 the hinge 20 is secured to the upper edge of an upwardly swinging carbon sheet 22 which is adapted to be passed downwardly between the rear and 90 intermediate record sheet sections. To one of the longitudinal or upright edges of the supporting sheet the other transversely swinging carbon sheet 23 is connected by 95 means of a flexible hinge 24 which is adapted to pass laterally between the front and intermediate sections of the record sheet, this last mentioned carbon, as shown in Figs. 1, 2 and 4 being thus connected with the supporting sheet at the left hand edge thereof. 105 After the sheets are assembled in this manner and a triplicate record has been produced on the several sections of the foremost sheet the several sections of this sheet and the carbon sheets may be readily separated 110 from each other by pulling downwardly on the front sheet which will cause the upper carbon sheet to be deflected toward the left away from the pile of record sheets and the several sections of the sheet 115 to be straightened out, and then by pulling forwardly and downwardly on the record sheet at an angle to the backing the tab of this sheet will be withdrawn from underneath the cross bar of the clamp and slipped off from the binding pins without tearing the openings of this tab and without disturbing the remaining record sheets of the 120 125

pile: While thus withdrawing the tab of the foremost sheet of the pile the upper carbon sheet is lifted slightly and its flap is temporarily removed from the binding pins 5 in order to release the tab of the foremost sheet. After the tab is withdrawn from these binding pins the flap is again turned downwardly over the binding pins so as to permit of again placing the carbon sheet 10 connected therewith between the rear and intermediate sections of the following record sheet preparatory to placing the other carbon sheet between the intermediate and front record sections for producing a triplicate 15 record of the next sale.

The cross bar of the clamping device bears against the flap of the rear carbon and holds the same in place together with the tabs of the record sheets which are 20 interposed between this flap and the supporting sheet thereof.

For convenience in separating or tearing apart the several sections of the sales sheets or slips the junction between the same may 25 be weakened by a line of perforations or otherwise to facilitate this operation in the usual and well known manner.

Instead of connecting the longitudinally swinging carbon with the upper edge of 30 the supporting sheet this carbon may be connected with the lower edge of the supporting sheet, as shown in Fig. 7 in which case the longitudinally swinging carbon 25 is connected with the lower edge of the supporting sheet 26 by a flexible hinge 27. This figure also shows the transversely swinging carbon 28 connected by a flexible hinge 29 with the right hand edge of the supporting sheet instead of at the left hand 40 edge thereof, as shown in Fig. 4. When the carbons are mounted in the manner indicated in Fig. 7 and used in connection with the sheets as mounted on the backing in Figs. 1 and 5 the transversely swinging carbon 28 is interposed between the rear and intermediate sheet sections and the longitudinally swinging carbon 25 is turned upwardly between the front and intermediate record sheet sections.

50 My improved manifold book or sales slips holder is very simple and inexpensive in construction, the same is not liable to get out of order, and the several parts can be easily manipulated without confusion so that a record of the sales may be quickly made and the parts of the record sheet dismembered and the sections of the next following record sheet readily interleaved with the carbon sheets preparatory to making 55 another triplicate record.

I claim as my invention:

1. A manifold book comprising a backing having a binding pin, adapted to receive a plurality of record sheets each of which has

a perforated tab at one end which receives 65 said pin, and a clamping device for holding said sheets in place comprising a cross bar engaging with the front side of the pile of tabs adjacent to the outer side of said pin, two longitudinal spring arms each having 70 one of its ends connected with one end of the cross bar, and a sliding connection between the other end of each arm and the backing.

2. A manifold book comprising a backing 75 having a plurality of binding pins, adapted to receive a plurality of record sheets each of which has a perforated tab at one end which receives said pins, and a clamping device for holding said sheets in place comprising a cross bar engaging with the front side of the pile of tabs adjacent to the outer sides of said pins, two longitudinal spring arms each having one of its ends connected with one end of the cross bar and provided 80 at its opposite end with a longitudinal guide loop, and guide pins arranged on said backing and having heads, each guide loop embracing one of said pins between the head of the latter and said backing. 85

3. A manifold book comprising a backing having a plurality of binding pins, adapted to receive a plurality of record sheets each of which has a perforated tab at one end which receives said pins, and a clamping 95 device for holding said sheets in place comprising a cross bar engaging with the front side of the pile of tabs adjacent to the outer sides of said pins, two longitudinal spring arms each having one of its ends connected with one end of the cross bar and provided 100 at its opposite end with a longitudinal guide loop, guide pins arranged on said backing and having heads, each guide loop embracing one of said pins between the head of the latter and said backing, and means for retaining said cross bar and arms against lateral displacement relatively to the backing. 105

4. A manifold book comprising a backing having a plurality of binding pins, adapted 110 to receive a plurality of record sheets each of which has a perforated tab at one end which receives said pins, and a clamping device for holding said sheets in place comprising a cross bar engaging with the front 115 side of the pile of tabs adjacent to the outer sides of said pins, two longitudinal spring arms each having one of its ends connected with one end of the cross bar and provided at its opposite end with a longitudinal guide loop, guide pins arranged on said 120 backing and having heads, each guide loop embracing one of said pins between the head of the latter and said backing, and retaining pins arranged on the backing and 125 engaging with the inner sides of said arms adjacent to the cross bar.

5. A manifold book comprising a backing

having a binding device adapted to engage
with one edge of a pile of record sheets,
and a clamping device for holding said
sheets in place having one part engaging
5 said sheets adjacent to said binding device
and another part slidably connected with
said backing.

Witness my hand this 7th day of July,
1914.

JOHN F. HUBER.
